UNITED STATES PATENT OFFICE.

GEORGE BRANTINGHAM, OF WEYMOUTH, ENGLAND.

ENGINE.

1,116,232.

Specification of Letters Patent.

Patented Nov. 3, 1914.

Application filed August 16, 1913. Serial No. 785,145.

To all whom it may concern:

Be it known that I, GEORGE BRANTINGHAM, subject of George V, King of Great Britain and Ireland, and residing at Wyke Regis, Weymouth, in the county of Dorset, England, have invented certain new and useful Improvements in Engines, of which the following is a specification.

This invention is primarily concerned 10 with marine engine governors, but it has in part a wider application as will herein-after appear. In its application to marine engine governors the invention relates to the type of governor in which the pitch- 15 ing of the ship imparts movement to a pendulum, rolling weight, tilting mercury tube, or other rocking member, which member actuates the throttle valve of the engine through an auxiliary engine the valve 20 whereof is coupled to the rocking member, and the piston rod to the throttle valve.

The invention consists in the provision of a particular form of engine, as hereinafter described and claimed, which, in its use in 25 connection with a marine-engine governor, is coupled thereto and to the throttle valve in the manner above referred to. In its use in connection with other apparatus it is suitably connected therewith.

30 The particular form of engine above referred to consists of a piston slidably fitted within a cylinder and provided with inlet and exhaust ports which are normally closed by a slide valve connected with the pendulum. Movement of the pendulum operates the slide valve which thereupon opens the ports thereby admitting pressure to one side of the cylinder, opening the other side to the exhaust, and moving the piston and 35 its rod. Although it would be possible to operate the throttle valve spindle direct from this piston rod I preferably provide a relay engine comprising a duplicate of the cylinder and its working parts which is 40 more powerful and which is operated from the smaller or primary cylinder, and I connect the duplicate piston rod direct to the throttle valve spindle.

In order that this invention may be 50 clearly understood and readily carried into effect, I will proceed to describe the same with reference to the accompanying drawings, which illustrate an embodiment of this invention, and wherein—

55 Figure 1 is a side elevation of the complete governor in which there are a pri-

mary cylinder and a relay cylinder. Fig. 2 is an elevation of the left hand or aft end of Fig. 1; Fig. 3 is a horizontal longitudinal section of the piston *b*. Fig. 4 is a section on line 4—4 of Fig. 3. Fig. 5 is a longitudinal axial cross section through the cylinder *b*, the rod *m*, and the pipe *b'*.

Referring to Figs. 1 and 2 of the drawings, *a*, *b*, are the cylinders, the upper and smaller cylinder *a* (hereinafter termed the "primary" cylinder) being mounted on a platform *a'* which is pivoted at *a*² to a fixed standard *c* and is also provided at its left hand end with a screw *a*³ bearing on a fixed standard *c'* and adapted to adjust the platform *a'* to a normally horizontal position, the amount of adjustment required depending upon the trim of the ship. The pendulum, shown at *d* is swung from its upper end at *d*¹ and is provided with a weight *d*² at its lower end. Projecting upwardly from the weight *d*² and passing through a longitudinal slot in the platform *a'* is a screwed pillar *d*³ connected by a rod *e* hinged to a lever *f* which in turn is pivoted at its upper end to the rod of the slide-valve *g* and slidably fitted at its lower end in a pin *f'* which is adapted to rock in the platform *a'*. The slide-valve *g* works 85 lengthwise in the hollow piston rod *h* which extends through both ends of the cylinder. The forward end of the piston rod of the primary cylinder *a* is connected by a rod *j* to a lever *k* which rocks on a pin *k'* in the platform *a'* and has its lower end slidably fitted in a pin *k*² adapted to rock in the forward end of the rod of the slide-valve *l* of the relay cylinder *b*. As in the case of the primary cylinder the slide-valve *l* works 90 lengthwise in the hollow piston rod *m* which latter extends through both ends of its cylinder *b*. The motive power, preferably compressed air, is admitted to the pistons of the primary and relay cylinders through 95 pipes *a*⁴ and *b'* respectively.

Reference will now be had to Figs. 3 and 4 for a detailed description of the slide-valve, piston and parts in immediate coöperation therewith. The diameter of the 105 piston in Figs. 3 and 4 corresponds to the internal diameter of the relay cylinder *b* and as the construction and arrangement of parts illustrated in these figures is the same as the corresponding parts of the primary 110 cylinder *a* the description thereof will serve for the two cylinders. The slide valve com-

prises two collars l' , l'' carried by the slide-valve rod and arranged normally to cover the ports m' , m'' in the piston m^3 . The ports m' , m'' respectively open out on opposite sides of the piston. Screwed into the piston m^3 is a pipe m^4 which is slidingly fitted into the pipe b' (Fig. 1) and conducts the compressed air from the latter into the space l^3 between the collars l' and l'' by means 10 of channels m^5 , m^6 and a peripheral channel m^6 (Fig. 4) there being intercommunication between the space l^3 , the radial channels m^5 , m^6 and the peripheral channel m^6 . The exhaust passes through the hole l^4 into 15 and through the hollow after end of the slide-valve l thence into the hollow after end of the piston rod m and away into the atmosphere.

n is a double eye for connecting the piston 20 rod m to the throttle valve spindle.

Fig. 5 may be considered as applying 25 equally well to the cylinder a and b , the only structural difference being the direction of the rods g and l . The reference letters of Fig. 5 may be converted to apply to the cylinder a by substituting h for m and g for l wherever they appear, the coefficients being the same.

The operation of the governor is as follows:—The piston m^3 having been connected up with a constant supply of compressed air, the pendulum d in swinging, due to rising of the stern of the ship, operates the slide-valve g and opens the ports in the corresponding piston. Compressed air then passes through one of the ports and the other port is opened to exhaust, with the result that the piston moves forward until its ports again become closed by the collars, 40 and moves the lever k , which in turn pushes the slide-valve l aft and thereby opens the ports in the piston m^3 of the relay cylinder. The latter, acting in the same way as the piston of the primary cylinder, then moves 45 the piston rod m aft thereby causing the throttle valve spindle to be worked.

I have found in practice that it is only necessary to move the slide-valve g of the primary cylinder about $\frac{1}{2}$ of an inch which 50 owing to the ratio between the lengths of the lever k on opposite sides of its fulcrum k' gives ample movement of the slide valve l of the relay cylinder. The longitudinal movement of the slide-valves g and l may 55 be limited by a split nut o (Fig. 1) fitted on to a reduced portion thereof and screwed into the hollow piston rod, the difference in length between the nut and the said reduced portion determining the longitudinal play 60 of the slide valve spindle.

By means of the screwed pillar d^2 and the 65 screwed lever f the connecting rod e can be raised and lowered according to the length of the ship, so as to obtain the required travel of the slide-valve g without unduly

straining the governor. The fore end of the connecting rod j can also be adjusted along the screwed portion of the lever k so as to vary the amount of movement of the latter.

In order to prevent the pendulum working when the stern of the ship descends below the normal level, the after end of the bottom portion of the weight d^2 of the pendulum is normally in engagement with an adjustable stop p it being necessary for the 70 governor to operate only when the stern rises to an abnormal extent. 75

Instead of a pendulum I may sometimes employ a mercury tube, rocking lever, tiltable bucket supplied with liquid, shot or the like, or other means which come into operation when the stern of the ship rises so as to work the slide-valve g . 80

By dispensing with the pendulum the engine above described may be used for other purposes e. g., in connection with steering gear, in place of hydraulic apparatus, appliances for sawing timber or sawing stone or marble. 85

I claim:—

1. In a marine engine governor, the combination with a pendulum of an auxiliary engine comprising a cylinder, a piston within said cylinder having a piston-rod, a valve chest and ports establishing communication between said valve chest and the opposite sides of said piston, a valve within said valve-chest adapted to open and close said ports, means for connecting said valve with said pendulum through which means said valve is operated, and operating means for communicating the motion of the piston rod to the throttle valve spindle of the engine to be governed. 90

2. In a marine engine governor, the combination with a pendulum of a primary auxiliary engine and a relay engine, each such engine comprising a cylinder, a piston within said cylinder having a piston rod, a valve chest, and ports establishing communication between said valve chest and the opposite sides of said piston, a valve within said valve-chest adapted to open and close said ports, means for connecting the valve of said primary auxiliary engine with said pendulum through which means the valve is operated, means for connecting the piston rod of said primary auxiliary engine with said valve of said relay engine, and means for communicating the motion of the piston rod of said relay engine to the throttle valve spindle of the engine to be governed. 105

3. In a marine engine governor, the combination with a pendulum of an auxiliary engine comprising a cylinder a piston within said cylinder having a piston-rod a valve chest and ports establishing communication between said valve-chest and the opposite sides of said piston, a valve within said valve-chest adapted to open and close said 110

120

125

130

ports, and adjustable means for connecting said valve with said pendulum through which means said valve is operated, and means for communicating the motion of the 5 piston-rod to the throttle valve spindle of the engine to be governed.

4. In a marine engine governor, the combination with a pendulum of an auxiliary engine comprising a cylinder, a piston within 10 said cylinder having a piston-rod, a valve chest and ports establishing communication between said valve chest and the opposite sides of said piston, a valve within said valve chest adapted to open and close said ports, means for connecting said valve with 15 said pendulum through which means said valve is operated, a bearing for supporting the pendulum, a platform for supporting the auxiliary engine, and means for adjusting 20 the inclination of said platform, and means for communicating the motion of the piston-rod to the throttle valve spindle of the engine to be governed.

5. In a marine engine governor, the combination with a pendulum of an auxiliary engine comprising a cylinder, a piston within 25 said cylinder having a piston-rod, a valve chest and ports establishing communication between said valve chest and the opposite sides of said piston, a valve within said 30 valve chest adapted to open and close said ports, means for connecting said valve with said pendulum through which means said valve is operated, means for conveying motive fluid to the piston, and means for com- 35

municating the motion of the piston rod to the throttle valve spindle of the engine to be governed.

6. In a marine engine governor, the combination with a pendulum of an auxiliary engine comprising a cylinder, a piston within 40 said cylinder having a piston-rod, a valve chest and ports establishing communication between said valve chest and the opposite sides of said piston, a valve within said 45 valve chest adapted to open and close said ports, means for connecting said valve with said pendulum through which means said valve is operated, means for limiting the longitudinal movement of said valve, and 50 means for communicating the motion of the piston rod to the throttle valve spindle of the engine to be governed.

7. An engine comprising a cylinder, a piston within said cylinder having a piston-rod, a valve chest within said piston and ports therein establishing communication between said valve chest and the opposite sides of said piston, a valve within said 55 valve-chest adapted to open and close said 60 ports, means for moving the valve so as to enable the engine to operate, means for conveying motive fluid to the valve chest, and means for permitting escape of exhaust.

In witness whereof I have hereunto set my 65 hand in the presence of two witnesses.

GEORGE BRANTINGHAM.
